CARL H. BISSELL, OF SYRACUSE; NEW YORK, ASSIGNOR TO CROUSE-HINDS COMPANY,
OF SYRACUSE, NEW YORK, A CORPORATION OF NEW YORK.

INCANDESCENT-ELECTRIC-LAMP SOCKET.

1,035,149.

Specification of Letters Patent. Patented Aug. 13, 1912.

Application filed October 6, 1910. Serial No. 585,626.

To all whom it may concern:

Be it known that I, CARL H. BISSELL, of 5
Syracuse, in the county of Onondaga and
State of New York, have invented a new
and useful Incandescent-Electric-Lamp
Socket, of which the following is a specification.

My invention has for its object the production of an incandescent electric lamp 10 socket, which is particularly simple and compact in construction and is composed of a minimum number of parts; and it consists in the combinations and constructions hereinafter set forth and claimed.

15 In describing this invention reference is had to the accompanying drawing in which like characters designate corresponding parts in all the views.

Figure 1 is an elevation, partly in section, 20 of this electric lamp socket. Fig. 2 is a top plan of the socket, the outer shell being removed. Fig. 3 is an inverted plan of parts seen in Fig. 2. Figs. 4 and 5 are sectional views taken, respectively, on lines "A—A" 25 and "B—B", Fig. 2. Figs. 6 and 7 are elevations, partly in section, of parts seen in Figs. 2 and 3. Figs. 8 and 9 are detail views of terminals of the socket.

1 is the base of this incandescent lamp 30 socket, the base being composed of any suitable insulating material and being formed with a recess including a slot-like portion 2 extending through diametrically opposite sides and through one end face thereof, the 35 recess having an enlargement 3 of the portion 2, the enlargement opening through said end face and laterally through another side portion of the base. The base is also formed with a lengthwise recess or groove 4 40 in one side thereof, this groove opening through the end face of the base through which the recess opens and being closed at its opposite end by a wall 5.

6 and 7 are wire terminals supported by 45 the base, the terminal 6 being located in the groove 8 formed in the side of the base 1 and opening into the slot-like portion 2 of the recess through the top thereof as best seen in Fig. 5. Said terminal 6 is also provided with a portion as 9 extending into the slot 2 and lying close to the end wall of the slot, and with an integral extension 10 projecting laterally from the portion 9 of the terminal 6. This extension 10 projects into the enlargement 3 of the recess

and is provided with a shelf portion 11 extending parallel to and opposed to the top or inner end wall of such enlargement 3 for retaining the key in position as hereinafter explained. The terminal 6 is held 60 in position by a fastening member as a screw 12 inserted through the upper end of the base and extending lengthwise of the base and into a perforation 13 formed in the extension 10. The terminal 6 is also, 65 provided with a binding screw 14 which threads into the perforation 15 in the portion of the terminal 6 lying in the groove 8.

The terminal 7 is located in the groove 4 and is provided with angular extensions 16 70 and 17 at its opposite ends, the extension 16 projecting across the end of the base through which the recess opens, and constituting the inner terminal for engaging the central terminal of the lamp. This extension projects into the sleeve terminal 18 which engages the outer terminal of the lamp. The other extension 17 is bent outwardly relatively to the axis of the base and terminates in a part which projects inwardly relatively to said axis and engages the wall 5 at the inner end of the groove 4; and the terminal 7 is secured to the base by a fastening member as the screw 19 extending lengthwise of the base through the 80 wall 5 and into a perforation 20 at the inner side of the outwardly bent portion of the extension 17. The terminal 7 is also provided with a binding screw 21 interposed between the extensions 16 and 17 of said 90 terminal.

The outer or sleeve terminal 18 is secured as by screws 22 to the end of the base through which the slot-like portion 2, and the enlargement 3 open and is provided with a head 23 at its end contiguous to the end of the base through which the screws 22 are passed, a portion of this head 23 extending across and closing the enlargement 3 of the recess 2.

24 is a switch through which the circuit to the terminal 18 is made and broken, said switch being arranged to break the circuit at two points and being here shown as consisting of a substantially U-shaped spring 105 secured between its ends to the base by a screw 25 extending into the top or inner end wall of the recess 2 and threading into a nut 26 embedded in the base from the rear end thereof. One arm of this spring is movable 110

100

95

105

110

into and out of contact with the terminal 6 and particularly the portion 9 thereof, and the other arm of such spring is movable into and out of contact with the head 23 of the sleeve terminal 18.

The switch 24 is operated by means of a key having a shank 27 journaled in the bearing formed partly by the top or inner end wall of the enlargement 3 of the recess 10 and partly by the portion 11 of the extension of the terminal 3, and a cam 28 mounted on the shank 27 and located between the arms of the spring 24.

A suitable handle or button 29 is mounted 15 on the other end of the shank 27.

As here shown the top or inner end wall of the recess is formed with a step 30 in which is formed a groove 31 Figs. 3, 4 and 7, extending transversely of the enlargement 20 3 and opening through one side of the slot-like portion 2 of the recess and the base is formed with a socket 32 Fig. 4 opening through the opposite wall of the slot-like portion 2 and aligned with the groove. The shank 27 is arranged in the groove and is 25 formed with an extension or stud 33 projecting beyond the cam 28 and into the socket 32. The shank is held in the groove by the shelf portion 11 of the extension 10, this portion extending across the open side 30 of the groove, and the extension 10 is shaped to fit the contour of the step 30. The step 30 is also formed with a shoulder 34 for engaging the edge of the extension 11 and holding the extension from movement in case of any looseness between the terminal 6 and its retaining screw.

The base and the sleeve terminal are 40 closed by the usual metallic shell 35 and lining 36, the shell having a suitable nipple 37 at its upper end through which the wires 38 and 39 are led.

My incandescent electric lamp socket is 45 particularly advantageous in that one of the wire terminals and one of the terminals for engaging the lamp terminals are formed integral and can be stamped in one operation and further in that the switch makes contact directly with the sleeve terminal 50 5 and is arranged in a particularly simple manner to break at two points thus providing for a simple and compact assembly of the parts of the socket.

The compactness of the lamp socket is 55 further enhanced by the fact that the key for operating the switch is held in position by the extension of one of the terminals and by the fact that each of the terminals is held in position by a single screw.

60. What I claim is:

1. An incandescent electric lamp socket comprising a single piece insulating base composed of a block of insulating material, wire terminals and lamp contact terminals 65 carried by the base; a switch interposed be-

tween one of the wire terminals and one of the lamp contact terminals, the switch comprising a substantially U-shaped spring secured between its ends to the base and having its arms movable respectively into and out of contact with one of the wire terminals and one of the lamp contact terminals, and a key having a cam located between the arms of the U-shaped spring for separating the arms to make contact with said terminals, substantially as and for the purpose described.

2. An incandescent electric lamp socket comprising an insulating base formed with a recess opening through one end thereof, wire terminals and lamp contact terminals carried by the base, one of the wire terminals being exposed at the side of the base and having a portion extending inwardly into the recess, and one of the lamp contact terminals being located to engage means movable in the recess, a switch member located within the recess and secured between its ends to the base and having opposite spring arms movable respectively into and out of contact with the inwardly extending portion of said one of the wire terminals and into and out of contact with said one of the lamp contact terminals, such arms being normally out of operative position to complete the circuit, and operating means for actuating said arms to complete the circuit, substantially as and for the purpose specified.

3. An incandescent electric lamp socket comprising an insulating base formed with a recess opening through one end thereof, wire terminals and lamp contact terminals carried by the base, one of the wire terminals extending at one side of the base substantially lengthwise thereof and having a portion extending laterally into the recess, and one of the lamp contact terminals having a part thereof extending across the open end of the recess, said base having a shoulder coincident with the plane of one face of said portion of said one of the wire terminals, and said wire terminal having a part thereof coacting with such shoulder, a switch member located within the recess and secured between its ends to the base and having opposite spring arms movable respectively into and out of contact with the laterally projecting portion of said one of the wire terminals and into and out of contact with said part of said one of the lamp contact terminals, such arms being normally out of operative position to complete the circuit, and operating means for actuating said arms to complete the circuit, substantially as and for the purpose set forth.

4. An incandescent electric lamp socket, comprising an insulating base formed with a recess opening through one end thereof, wire terminals and lamp contact terminals

carried by the base, one of the wire terminals extending into the recess and one of the lamp contact terminals comprising a sleeve mounted on the end of the base through which the recess opens and having a head extending across the open end of the recess, a U-shaped switch located within the recess and secured between its ends to the base and having its arms movable respectively into and out of contact with said one of the wire terminals and said head of the sleeve terminal, and a key comprising a cam located between the arms of the U-shaped switch for separating the arms and moving the same into contact with said wire terminal and the head of the sleeve terminal, substantially as and for the purpose specified.

5. An incandescent electric lamp socket comprising an insulating base formed with a recess in one side thereof and opening through one end and terminating short of the other end of the base, said recess extending in the same general direction as the axis of the base, electric conducting members carried by the base and constituting wire terminals and lamp contact terminals, one of said members extending lengthwise in the recess and being provided with wire securing means between its ends, said member having one end extended toward said axis and overlying one end of the base to form a lamp contact terminal, and having its other end extended outwardly relatively to said axis between the wire securing means and the closed end of the recess, and terminating in a part extending inwardly relatively to said axis and engaging the wall of the closed end of the recess, and holding means extending lengthwise of said axis through said wall at the closed end of the recess and coacting with said terminating part and terminating at the inner side of the outwardly extended portion of said member, substantially as and for the purpose set forth.

6. An incandescent electric lamp socket comprising an insulating base having a recess opening through a side and one end of the base, wire terminals and lamp contact terminals supported by the base, one of the wire terminals having an extension forming a bearing, a switch in the recess, and a key for controlling the operation of the switch, the key having a revoluble shank coacting with said bearing and having a cam for controlling the operation of the switch, substantially as and for the purpose described.

7. An incandescent electric lamp socket comprising an insulating base having a recess opening through a side and one end of the base, wire terminals and lamp contact terminals supported by the base, one of the wire terminals having an extension extending below the inner end wall of a portion

of the recess and opposed to said wall and forming a bearing, a switch in the recess, and a key for controlling the operation of the switch, the key having a shank coöperating with the bearing and a cam for controlling the operation of the switch, the shank being held in position by said extension, substantially as and for the purpose described.

8. An incandescent electric lamp socket comprising an insulating base having a recess opening through a contact side and one end of the base, wire terminals and lamp terminals supported by the base, one of the wire terminals having an extension below the inner wall of a portion of the recess and opposed to said wall and forming a bearing, a single fastening member for holding the terminal and its extension in position, a switch in the recess, and a key for controlling the operation of the switch, the key having a shank coöperating with the bearing and a cam for controlling the operation of the switch, the shank being held in position by said extension, substantially as and for the purpose specified.

9. An incandescent electric lamp socket comprising an insulating base having a recess opening through a side and one end of the base and a transverse groove formed in the end wall of a portion of the recess, wire terminals and lamp contact terminals supported by the base, one of the wire terminals having an integral extension extending across the groove and coöperating therewith to form a bearing, a single fastening member for holding the terminal and its extension in position, a switch in the recess, and a key for controlling the operation of the switch, the key having a shank journaled in the bearing, substantially as and for the purpose set forth.

10. An incandescent electric lamp socket comprising a one piece insulating base, having a recess, and a bearing arranged with its axis transversely of the recess and having portions located in axial alinement on opposite sides of the recess, one of said portions being in the form of a socket and the other in the form of a groove, wire terminals and lamp contact terminals supported by the base, a switch interposed between one of the wire terminals and one of the lamp contact terminals, and being located in the recess, a key for controlling the operation of the switch including a shank journaled in the socket and the groove of the bearing and means fixed relatively to the base for holding the shank in the groove of the bearing, substantially as and for the purpose described.

11. An incandescent electric lamp socket comprising an insulating base, having a recess opening through one end of the base, the recess including a slot-like portion and

- an enlargement, and the inner end wall of the enlargement being formed with a groove extending transversely of the slot-like portion and opening into said slot-like portion 5 through one side wall thereof, and the base being formed with a socket opening through the opposite wall of the slot-like portion of the recess and alined with the groove, wire terminals and lamp contact terminals carried 10 by the base, one of the wire terminals having an extension lying across the open side of the groove, a switch in the recess and interposed between one of the wire terminals and one of the lamp contact terminals, and 15 a key including a shank arranged in the groove and having its end supported in the socket and a cam mounted on the shank for operating the switch, substantially as and for the purpose specified.
- 20 12. An incandescent electric lamp socket comprising an insulating base, having a recess opening through the side and one end of the base and a groove formed in the inner end wall of a portion of the recess, wire terminals and lamp contact terminals carried by the base, one of the wire terminals being arranged at the side of the base and extending into the recess and having an extension lying across the groove and coöperating 25 with the groove to form a bearing, a single fastening member for holding said wire terminal and its extension in position, a switch in the recess and interposed between one of the wire terminals and one of the lamp contact terminals, the switch being a substantially U-shaped spring secured between its ends to the base within the recess and having its ends movable into and out of electrical connection with said wire terminal and one of the lamp contact terminals, and 30 a key having a shank journaled in the bearing and being held therein by the extension
- 5 of said wire terminal, the key having a cam between the arms of the U-shaped spring for separating the arms to make connection 45 with said terminals, substantially as and for the purpose set forth.
13. An incandescent electric lamp socket comprising an insulating base having a recess opening through the side and one end 50 of the base, and a groove formed in the end wall of a portion of the recess, wire terminals and lamp contact terminals supported by the base, one of the wire terminals being secured to the side of the base and having an angular extension overlying the end of the base through which the recess opens and constituting the central lamp contact terminal, and the other lamp contact terminal comprising a sleeve mounted on said end of 55 the base, and the other wire terminal extending into the recess and having an angular extension extending across said groove and coöperating therewith to form a bearing, a single fastening member for holding 60 each of the wire terminals and their extensions in position, a switch in the recess and interposed between the sleeve terminal and the wire terminal extending into the recess, and a key having a shank journaled in the 65 bearing and held in position by the extension of the wire terminal, the key having a cam for controlling the operation of the switch, substantially as and for the purpose described.
- 75 In testimony whereof, I have hereunto signed my name in the presence of two attesting witnesses, at Syracuse, in the county of Onondaga, in the State of New York, this 3rd day of October 1910.
- CARL H. BISSELL.
